EDWIN F. PORTER, OF BOSTON, MASSACHUSETTS, ASSIGNOR TO MOVING PICTURE APPLIANCE CO., A CORPORATION OF MASSACHUSETTS.

PROJECTING APPARATUS FOR MOVING-PICTURE MACHINES.

1,356,787.

Specification of Letters Patent. Patented Oct. 26, 1920.

Application filed April 26, 1917. Serial No. 164,769.

To all whom it may concern:

Be it known that I, EDWIN F. PORTER, a subject of the King of England, residing at Boston, in the county of Suffolk, Commonwealth of Massachusetts, have invented a certain new and useful Improvement in Projecting Apparatus for Moving-Picture Machines, of which the following is a specification.

10 My invention relates to that type of projecting apparatus for a moving picture machine designed to provide a continuous series of projected images without interrupting the movement of the film strip or successive pictures to be reproduced and without interrupting illumination upon the screen. It has been my further object to produce a machine which shall be simple, inexpensive and easy of operation. My device may be best 15 understood by reference to the accompanying drawings, in which Figure 1 is a front view of those parts of my device lying behind the framing screen; Fig. 2 is a plan view; Fig. 3 is a side view of certain parts 20 of my device lying to the left of the dotted line 3—3 of Fig. 2, viewed in the direction of the arrow; Figs. 4, 5 and 6 are diagrams, which will be hereinafter explained, illustrating the optical principles and mode of 25 operation of my invention.

Referring now more specifically to the drawings, A is a supporting frame in which is journaled shaft B, which has fast thereon the operating pulley b which is grooved to 30 carry a belt. The film strip D is provided with perforations in its edges, which perforations are adapted to register with the teeth c of the sprocket roller C in the usual manner. A small idle roller c' is journaled in 35 the frame below the sprocket roller C for the purpose of supporting the film and holding it in engagement with the sprocket roller C. Across the end of projections a, a' on frame A is mounted an aperture plate E 40 provided with an aperture e (indicated by dotted lines in Fig. 1). The shaft B has also fast thereon the spiral gears F, F', which mesh with gears G, G', which are fast upon shafts g, g' which are journaled in 45 frame A at right angles to shaft B on either side of the projections supporting the aperture plate. The gears are arranged to rotate shafts g, g' in the opposite directions indicated by the arrows in Fig. 1. Fixed fast 50 to shaft g between flanges h, h' is a circular 55

glass disk I, the outer surface of which is flat and the inner surface of which is beveled toward the circumference so as to form four plane prisms i of equal angle and dimension, there being necessarily radial ridges 60 i' between the prisms. Upon shaft g' between flanges h², h³ is a similar glass disk I' arranged to overlap disk I, its flat side being inward so as to permit the disks to be in close juxtaposition when in motion by 65 the rotation of the respective shafts on which they are mounted. The disks I, I' are so arranged upon their respective shafts that corresponding points upon the prismatic surfaces overlap each other. The flanges h, h' 70 and h², h³, between which the disks I, I' are supported, are provided with set screws j which afford means of adjustment of the position of disks I, I' both in respect to each other and in respect to proximity to 75 the objective. Mounted across an opening in frame A in alignment with the opening in the aperture plate E and in alignment with the overlapping parts of the disks I, I', is tube J carrying the rear lens (not shown) 80 of the usual objective. The front lens K of the objective is mounted within the annular rim k which is borne by the integral arm L which is rotatably and slidably mounted by means of slot l on rod M which is rigidly supported on frame A. The opposite end of the arm L is supported by the arm l' which rests on the cam g² which is fast on the rotatable shaft g. A spring N, 85 one end of which is fastened to rod M and the other end of which bears loosely against a pin l² on the arm L exerts a constant force actuating arm L downward and outward toward cam g² causing the lug l³ on the inside of arm L forming a cam shoe to bear against cam g³ which is fast on the end of the 90 rotatable shaft g'. The operation of the machine is as follows: The film D moves downward by the rotation of sprocket roller C upon the rotating shaft B due to the engagement of film perforations (not shown) with the sprocket teeth c, closely behind aperture plate E, the aperture of which is of the length of three or more (but preferably three) pictures on 95 the film. The gears F, F' and G, G' are so arranged as to rotate disks I, I' in the opposite directions indicated by the arrows thereon on Fig. 1 at such a rate that the film strip moves down the length of a single 100 105 110

picture thereon for each quarter revolution of the disks. The relation of the disks to the film strip is so adjusted that when a dividing line between prisms on one disk overlies a corresponding dividing line on the other disk opposite the center of aperture e , a dividing line between film pictures is also opposite the center of the aperture e and opposite said dividing lines on said prisms.

10 It will be readily apparent that upon the revolution of disks I, I', one-eighth of a turn into the position in Fig. 1, the beam of light from a source of light passing through condenser X, as shown in Fig. 4, will pass

15 through the film and aperture in the aperture plate and through the objectives between which the disks I and I' present parallel vertical faces, and the film picture which by the movement of the film has now

20 come into central position in the aperture of the aperture plate and in relation to the focal axis of the system will be reproduced as the central image of the three projected pictures and is thrown upon a screen. The

25 pictures above and below it may be obscured by the framing screen O indicated in Fig. 3 which may be adjustably connected with frame A or otherwise independently supported and which has an aperture sufficient

30 to permit the display of the picture intended to be represented on the screen while obscuring the images of the pictures above and below. As the film moves downwardly the

35 continued rotation of the disks I, I' will bring about a change in the relation of their surfaces presented to the beam of light, there appearing an angular disposition of the outer surfaces of the disks which surfaces slant downwardly and outwardly from

40 the top thus producing a refracting element of increasing power which counteracts or compensates the effect of the downward movement of the film which would otherwise result in the upward movement of the projected image on the screen thus holding this

45 image in place upon the screen. From the relation of the movement of the parts of the machine, it will be apparent that when this film picture which was the central film picture has moved downwardly about a half of its width, a change occurs immediately in the prismatic form of that portion of the disks which is in the path of the beam of light as the ridges of the disks approach

50 alinement presenting a prismatic form wherein the outer surfaces of the disks slant downwardly and inwardly thus suddenly throwing up the image which has been represented on the screen to a position where

55 it may be obscured by the framing screen O. There is immediately brought into view however upon the screen an image which is reproduced from the film picture immediately above the film picture, the image of

60 which was previously reproduced, the rays

producing which image are however thrown up sufficiently to bring the image on the screen by the refraction of this new prism now affecting them, which prism is of opposite character to that previously appearing 70 in the beam of light. The effect of the continued movement of the film is compensated so as to cause the image of the picture now being produced to remain stationary on the screen instead of rising by the prismatic 75 form afforded by the relation of the outer surfaces of the disks, which prismatic form instead of refracting the picture rays downward to an increasing degree now has the equally compensating effect of refracting 80 them upward to a continuously diminishing extent until the non-refracting position of the disks shown in Fig. 1 and diagrammatical Fig. 4 is reached and passed when the compensating effect gradually becomes that 85 of refracting downward more and more as the film passes through the lower area of the beam of light below the focal axis, from which position it would otherwise be reproduced higher upon the screen. As this film 90 picture now being reproduced continues its downward movement, the light beam passing therethrough again encounters the sudden change of prismatic influence of the disks, and are thrown upward above the 95 screen area as before while the picture beams of the picture above are cast upon the screen.

Thus it will be seen that in the cycle of operation of the device the rays of light 100 from a film picture in the upper part of a projected beam above the focal axis of the system are projected upon the screen passing through a prism that tends to throw them upward with ever diminishing power, to 105 compensate for the effect of film movement until the film picture is on the focal axis of the system when the revolving disks present an area which is non-refracting in the vertical plane and thereafter the film picture 110 passes into the light beam below the focal axis of the system and the beam of light passing therethrough encounters a gradually growing prism of opposite character which tends to refract the beam downwardly 115 to an increasing degree until suddenly the beam encounters a fully developed prism of changed character which throws the picture beam up and off of the screen, and substitutes upon the screen the image of the next 120 succeeding film picture. It is apparent that if the image of the picture is to be kept upon the screen notwithstanding the fact that the picture moves from above to below the focal axis of the system, it must be influenced by 125 opposite prismatic forms, the apex of one succeeding the apex of the other, the first prismatic form gradually collapsing until it disappears and the second prismatic form begins to grow. But when it becomes neces- 130

sary to suddenly deflect the picture beam so as to throw its image off the screen and substitute that of the picture above it, an abrupt change of prismatic influence is necessary and this is afforded by the sudden appearance of a fully developed prism of opposite character to that preceding it, occasioned by the passage through the beam of light of the radial ridges upon the revolving 10 disks.

By reference to Fig. 5, it will be seen that the beam of light passing through the system in the position therein shown will be refracted upwardly to a point above the optical center of the outer objective through which it is again refracted downwardly to its intended position upon the screen. This slight vertical displacement of the beam of light at the point occupied by the framing 20 screen will cause the shadow of the edges of the aperture of the screen to fluctuate slightly upon the edges of the picture screen and to eliminate the objectionable appearance of this shadow fluctuation, I prefer to make the 25 edges of the picture screen to be used with my device of a dark, light-absorbing material.

Inasmuch as screen distances vary and it becomes necessary to so adjust the device 30 that successive pictures will register upon the screen I have provided means for doing this by adjusting the location of the prismatic disks I, I' by sliding them upon shafts g, g' after loosening flanges h, h' and h², h³, 35 by unscrewing set screws j. It will be apparent from examination of the diagram shown in Fig. 5 that the farther the rotating disks are removed from the outer objective when in the position shown in that figure, 40 the higher the rays of light passing through the disk will impinge above the optical center of the outer objective or the lower beneath it when the opposite prismatic form is in operation. It will be seen also that the 45 refraction of light by the objective is counter to that of the prism formed by the disks thereby partially negating the refraction. Therefore if the prisms presented by the revolving disks are too strong for a given 50 screen distance their effect may be weakened by moving them away from the outer objective or vice versa.

Although I have spoken of the compensation of the movement of the film by the action of the revolving prismatic disks, it is not to be understood that I intend to represent that it is fully compensated as it is to be noted that the upward speed of the overlapping parts of the revolving disks, in the 60 sense of vertical direction, is variable because of their circular movement, and the vertical speed is greatest at the center of the beam of light and increases as that point is approached and diminishes after that point 65 is passed. Some means of compensation

must be provided for this variability. The effect of those elements of my device which I have already explained would be to reproduce upon the screen approximately steady pictures affected by a slight, regular, vertical fluctuation. To correct this and to produce what is required in commercial reproduction of pictures, a "rock steady" picture, I have provided the means for compensation involved in the movable mounting of the 75 outer objective.

The rotation of shaft g will also rotate cam g² upon which slides the cam shoe which is afforded by the end of arm l' which is in rigid relation with objective K. It will be 80 observed in Fig. 1 that the cam g² has four throws the peaks of which are each so placed in relation to a corresponding prism of the rotary disk I that the objective K is brought to its highest point of elevation shortly before the ridges of the disk pass into the beam of light thereby causing a change in its refraction. Hence assuming the device to be moving from the position in which its parts are shown in Fig. 1, it will be apparent that a slight movement will bring the objective to its highest point and that it will then begin to drop as the rotating disks present to the beam of light a prism, the sides of which diverge as they approach the base, 95 which prism upon the rotation of the disks is being constantly built up so that the angle of divergence of its sides is constantly increasing, thus causing the rays from the film picture which is being displayed to be moved 100 downwardly at substantially the same rate that they are moved upwardly by the downward motion of the film. But this compensation is not complete owing to the variation of speed in the growth of the prism, it growing more slowly toward its base as the disks revolve due to the variation of speed at different points in the same vertical line. Hence the motion of the film which is traveling downward at uniform speed tends, as it 105 reaches a low position where the picture beam is under the influence of the less rapidly growing influence of the prism, to cast the picture up on the screen to a degree which is not overcome by the action of the 110 prism presented by the disks. Thus it becomes necessary to move the outer objective K slightly downward, a motion which is at this time permitted by the cam g², which motion is such as to retain the picture in its 115 place upon the screen as far as vertical displacement is concerned. It will be apparent that the action of the revolving disks, notwithstanding the fact that since they overlap one compensates for the lateral displacement of the beam of light occasioned by the other, nevertheless jointly cause a varying lateral refraction of the beam of light owing to the fact that the angle of the outer surfaces varies as the disks revolve, thus caus- 120 125 130

ing diversity in their angular relation to the light rays, a feature which is illustrated diagrammatically in Fig. 6 which shows the ray of light as it is refracted when the surfaces of light as it is refracted when the surfaces 5 present an extreme angle as shown by solid lines, and a lesser angle as shown by dotted lines. To steady the picture on the screen against lateral fluctuation and compensate for this variation, I have provided the cam 10 g^3 against which bears cam shoe l^3 on the inside of arm L. The effect of this cam g^3 is to move the arm L and the outer objective K borne thereby to the right, when viewed in the position of Fig. 1 as a prism growing 15 toward its lower portion by the revolution of the disks is in effect in the beam of light, thereby causing the outer surfaces of the disks in the horizontal plane more nearly to approach a parallel relation thus tending to 20 throw the picture beam to the left, an effect which is compensated by the attendant movement of the outer objective K toward the right. The exact shaping of cams g^2 , g^3 , so as to effect a complete steadyng of the 25 picture is to some degree a matter of experimental grinding of the cam surfaces while the machine is being operated at very slow speed as slight defects or irregularities in the construction of the disks I, I', or the 30 parts whereon they are mounted may also require to be compensated through the shaping of these cams. It will be understood of course that the operation of the cams at times when the prismatic condition presented by the revolution of the disks is the 35 opposite from that above stated, viz., when they present to the beam of light a prism, the sides of which diverge toward the top is the reverse from that which I have previously explained.

Although I have shown a construction in which the circular glass disks are provided with four plane prisms nevertheless I do not wish to be understood to be limited to 45 that number as it will be apparent that a varying number may be employed provided the construction of the motion imparting parts is such as to cause the stated relation of film picture movement with disk movement whereby the disks rotate the distance 50 of one of their plane prisms during the movement of the film strip a single picture distance.

The compensating effects afforded by the 55 movement of the outer objective K might of course also be obtained by moving the inner objective while leaving the outer objective fixedly mounted but I have preferred to move the outer objective as this 60 is apparently the more simple and convenient mechanical operation. While I am aware that moving picture machines have been constructed in a manner whereby it has been sought to obtain continuous projection from a continuously moving film

strip, the picture being retained in position by means of moving prisms or lenses placed in the picture beam, nevertheless such devices have not been successful in overcoming the inherent tendencies of such devices 70 to cause fluctuation of the picture beam and the image projected upon the screen. The lens or prism devised to compensate for the effect of the film movement has been so shaped as to be inadequate for this purpose without causing uncompensated fluctuation of the picture beam or temporary obscurement thereof. With my device however, it is apparent that there is true, continuous projection, there always being a 80 picture upon the screen and no loss of light from the dimming of the picture. My device has the further advantage of being both simple and cheap of construction and easy 85 of operation.

Having thus fully described my invention, what I claim is:

1. In a device of the character specified the combination of means for continuously moving a film strip, an objective, movable refracting members so shaped that when moved they may present to a beam of light passing through said film strip and said objective varying, successive prismatic forms, each of opposite refracting character, one growing and increasing in its power of refraction and the other diminishing and decreasing in its power of refraction, the growing prismatic form being followed abruptly by a prismatic form fully 100 developed and of opposite refracting character which diminishes and is succeeded in turn by said growing prismatic form, said refracting members being adapted successively to substitute upon a screen the images of successive film pictures and retain said images upon said screen, each during the period of its display, notwithstanding the movement of said film strip, means for compensating for inadequacy of said refracting 110 members to completely counteract the effect of the movement of said film strip, and means for preventing the lateral fluctuation of images upon the screen due to the varying lateral refraction of said refracting 115 members at different stages of their operation.

2. In a device of the character specified the combination of means for continuously moving a film strip, an objective, movable 120 refracting members so shaped that when moved they may present to a beam of light passing through said film strip and said objective varying, successive prismatic forms, each of opposite refracting character, one 125 growing and increasing in its power of refraction and the other diminishing and decreasing in its power of refraction, the growing prismatic form being followed abruptly by a prismatic form fully developed 130

and of opposite refracting character which diminishes and is succeeded in turn by said growing prismatic form, said refracting members being adapted successively to substitute upon a screen the images of successive film pictures and retain said images upon said screen, each during the period of its display, notwithstanding the movement of said film strip, means for compensating for inadequacy of said refracting members to completely counteract the effect of the movement of said film strip, means for preventing the lateral fluctuation of images upon the screen due to the varying lateral refraction of said refracting members at different stages of their operation, and means for compensating for accidental refraction due to imperfections of construction of said movable refracting members or 20 the parts whereby they are actuated.

3. In a device of the character specified the combination of means affording a passage for a beam of light, means for mounting a film strip across said passage, a movably mounted objective arranged to influence the beam of light passing through said film strip, a pair of shafts rotatably mounted one on each side of said objective, two glass disks, each affixed to one of said shafts in a manner whereby their peripheries may overlap within said beam of light, said disks being 25 beveled upon their remote sides so as to form a uniform series of plane prisms, and means for rotating said shafts in opposite directions and actuating said film strip in a manner whereby it may be moved the 30 distance of a picture thereon while said disks are rotating a distance equal to one of their plane prisms, a cam on one of said shafts 35 and a cam shoe in connection with said objective, said cam being arranged to elevate and lower said objective.

4. In a device of the character specified the combination of means affording a passage for a beam of light, means for mounting a film strip across said passage, an objective arranged to influence the beam of light passing through said film strip, a pair of shafts rotatably mounted one on each 45 side of said objective, two glass disks, each affixed to one of said shafts in a manner whereby their peripheries may overlap within said beam of light, said disks being beveled upon their remote sides so as to 50 form a uniform series of plane prisms, and means for rotating said shafts in opposite directions and actuating said film strip

in a manner whereby it may be moved the distance of a picture thereon while said disks are rotating a distance equal to one of their plane prisms, a cam mounted on one of said rotatable shafts, an arm slidably supported whereon said objective is mounted, a lug on said arm arranged to bear on said cam and a spring arranged to actuate 60 said arm so as to hold said arm in engagement with the cam, said cam being arranged to give said arm and the objective carried thereby a lateral reciprocating movement.

5. In a device of the character specified the combination of means affording a passage for a beam of light, means for mounting a film strip across said passage, an objective arranged to influence the beam of light passing through said film strip, a pair of shafts rotatably mounted one on each side of said objective, two glass disks, each 65 affixed to one of said shafts in a manner whereby their peripheries may overlap within said beam of light, said disks being 70 beveled upon their remote sides so as to form a uniform series of plane prisms, and means for rotating said shafts in opposite directions and actuating said film strip in a manner whereby it may be moved the 75 distance of a picture thereon while said disks are rotating a distance equal to one of their plane prisms, a cam on each of said shafts, 80 members connected with said arm and arranged to bear upon said cams which cams are arranged to elevate and lower said arm whereon said objective is mounted and to give the same a lateral reciprocating movement, 85 a spring arranged to actuate said arm so as to hold said members connected therewith in engagement with said cams.

6. In a device of the character specified the combination of means for projecting an 100 uninterrupted beam of light, means for continuously moving a film strip across said beam of light, a movably mounted objective, arranged to be moved in a plane transverse to said beam of light, movable refracting 105 means for successively substituting upon a screen the images of successive film pictures and retaining said images upon said screen each during the period of its display, notwithstanding the movement of said film 110 strip and means for moving said objective.

In testimony whereof I have hereunto affixed my signature.

EDWIN F. PORTER.
